UNITED STATES PATENT OFFICE.

JOHN M. SHIELDS, OF CHICAGO, ILLINOIS, ASSIGNOR TO F. H. NOBLE & COMPANY, OF CHICAGO, ILLINOIS, A CORPORATION OF ILLINOIS.

SPRING-HINGE.

1,327,065.

Specification of Letters Patent.

Patented Jan. 6, 1920.

Application filed November 29, 1918. Serial No. 264,520.

To all whom it may concern:

Be it known that I, JOHN M. SHIELDS, a citizen of the United States, residing at Chicago, in the county of Cook and State 5 of Illinois, have invented certain new and useful Improvements in Spring-Hinges, of which the following is a specification.

My invention relates to spring hinges of the kind that are largely used upon small 10 boxes or cases used as containers for a great variety of articles, such as jewelry, ornaments, toilet articles, and many other objects. It has for its purpose the provision of a spring hinge which shall be effective in 15 action, operate smoothly and with certainty and come to a stop at open position without shock or jar, and which shall be simple and economical to construct. With this purpose and the foregoing advantages in view I have 20 devised and invented the novel spring hinge hereinafter described and which is illustrated in the accompanying drawing, the essential elements of my invention being more particularly pointed out in the appended 25 claims.

Of the figures of the drawing, Figure 1 is a perspective of a box to which a preferred form of my novel spring hinge is applied; Fig. 2 is a side view showing the 30 position occupied by the parts of the hinge and spring when the box is closed; Fig. 3 is a similar view with the box open; and Fig. 4 is a perspective of a portion of the hinge showing a modified form of spring.

The same reference characters indicate the same parts in all the figures of the drawing.

As shown, the hinge members 1 and 2 of the preferred form of my device may be 40 formed separately and attached respectively to the back side of the body member 3 and the back side of the cover member 4 of the box,—in the present instance by lugs struck up from the sides (the parts of the box being constructed of sheet metal) and extending 45 through slots in the hinge leaves and bent down to clamp the hinge leaves to the box members. However, the sides of the box body and box cover may be hinged together and constitute the leaves of the 50 hinge, if preferred.

The spring member 5 of my device is formed of a wire possessing a high degree of stiffness, elasticity and resiliency, the kind used in the manufacture of pianos as 55 strings for the instrument being suitable for the purpose. This spring is of the curved form shown, and comprises a semi-circular upper portion 6, the ends of which are continuous with two curved portions 7—7, 60 which latter portions curve outwardly or away from the hinge leaves around the knuckle of the hinge and approach each other below the hinge joint where they merge into opposite, outwardly curved end 65 portions 8—8 lying in a common plane. The center of the top portion 6 hooks over a hooked lug 9 struck up from the metal of the upper hinge leaf at a point remote from the axis of the hinge, and the ends of the 70 lower portions 8—8 hook under similar hooked lugs 10—10 struck up from the metal of the lower hinge leaf. The contour of the spring and the formation and arrangement of the parts are such that in open position 75 the semi-circular portion 6 of the spring will lie flat against the outer portion of the upper hinge leaf and the end portions 8—8 flat against the outer portion of the lower leaf, while the central portions 7 of the 80 spring will curve around and away from the hinge joint and form a resilient lower bridge yieldingly and elastically maintaining the hinge and box members in open position. It will be understood that when 85 the box is closed the spring exerts a tension pulling on the lugs 9 and 10—10 on a line inside the axis of the hinge which yieldingly holds the box members in closed position, and that when the box is opened the spring 90 is first extended and then when the box is partly open and, as the line of pull passes to the outside of the axis of the hinge, contracts to continue the opening movement. In the closed position the spring as a whole 95 is contracted between its points of attachment and extends farthest away from the hinge joint, the upper portion 6 and lower portion 8—8 being inclined away from the faces of the hinge leaves. In opening the 100 box, however, the portions 6 and 8—8 of the spring, pivoting upon the lugs to which they

are connected, swing toward the hinge members, and when they come into contact with the faces of the hinge leaves the latter act as stops and the intermediate curved portions 7-7 act together as a buffer, with the result that excess opening action of the spring, under whatever momentum the lid may have, meets with a cushioned resistance and the lid comes to a stop smoothly and without shock or jar. The inclined or oblique position of the curved portions 7-7 with respect to the axis of the hinge enables the curve to be made longer than if the arc described by such portions ran at right angles to the axis; and provides a comparatively long intermediate spring portion having a smooth uniform action.

In Fig. 4 I have illustrated a modified form of my invention, in which the spring 20 is of a different shape, but has the mode of operation above described. In this modified form the semicircular upper portion 11 of the spring merges into an intermediate obliquely arranged portion 12 which curves 25 across and around the knuckle of the hinge and on the lower side merges into a semicircular lower portion 13, the general outline being that of the letter S bent backwardly at top and bottom, and with a forward swell or bend near its center. The top portion hooks over a lug 14 struck up from the upper hinge leaf and the lower portion over a similar lug 15 struck up from the lower hinge leaf, and the spring pivots 30 on these lugs and the semicircular upper and lower portions stop against the faces of the hinge leaves and the intermediate portion acts as a cushion in the same manner as the corresponding parts act in the form of my 35 invention first described.

It is obvious that the preferred form of spring which has been described may be regarded as a double spring member, the parts of which each have at one end a plane portion 40 which is pivoted to the outer part of one hinge leaf and at the other end a plane portion pivoted to the outer part of the other hinge leaf and which have an intermediate curved or bowed connecting portion 45 extending obliquely across and around the central portion of the hinge to provide a cushioned stop when the plane portions of the spring bring up against the faces of the hinge plates, as in the case of the corresponding parts of the modified form of my 50 device illustrated in Fig. 4. It is furthermore evident that the oblique position of the central portion of the spring in both forms of my invention is advantageous, though not 55 indispensable, and that a plane portion may be provided at one end of the spring only, although I consider it desirable to form the spring in such manner as to provide a stopping action at both ends thereof. I therefore do not limit my invention to the par-

ticular forms of spring described, although such forms are simple, effective and desirable, and the first mentioned and preferred form is specifically claimed in certain of the claims.

I claim:

1. In combination with a pair of hinged leaves, a spring having its opposite ends pivotally connected with the outer portions of such leaves and extending around the knuckle of the hinge, said spring being arranged to stop against a hinge leaf at a point thereon intermediate the point of attachment of the spring and the knuckle of the hinge and the central portion of said spring being out of contact with such knuckle when the hinge is in open position. 75

2. In combination with a pair of flat hinged leaves, a spring having opposite outer plane portions pivotally connected at their extremities with the outer portions of such leaves and an intermediate portion extending around the knuckle of the hinge, the plane outer portions of said spring being arranged to stop against the faces of said hinge leaves and the central portion of said spring being out of contact with said knuckle when the hinge is in open position. 80

3. In combination with a pair of hinged leaves, a wire spring having a semi-circular upper portion, curved intermediate portions connected with said upper portion and extending around the knuckle of the hinge, and oppositely arranged end portions lying in one and the same plane, the top of said upper portion being pivoted to the outer portion of one hinge leaf and said end portions of the spring being pivoted to the other hinge leaf, and the central portion of said spring being out of contact with said knuckle 95 when the hinge is in open position. 100

4. In combination with a pair of hinged leaves, a wire spring having semicircular upper portion, curved intermediate portions connected with said upper portion and extending toward each other around the knuckle of the hinge, and end portions extending outwardly away from each other and arranged in one and the same plane, the top of said upper portion being pivoted to the outer portion of one hinge leaf and said end portions of the spring being pivoted to the other hinge leaf, and the central portion of said spring being out of contact with said knuckle 110 when the hinge is in open position. 115

5. In combination with a pair of hinged sheet metal leaves, a wire spring having semicircular upper portion, curved intermediate portions connected with said upper portion and extending toward each other around the knuckle of the hinge, and end portions extending outwardly away from each other and arranged in one and the same plane, the upper hinge leaf being formed 120 with a lug pivotally engaged by the top of 125

said upper portion of the spring and the lower hinge leaf being formed with a pair of lugs pivotally engaged by said end portions of the spring and the central portion 5 of said spring being out of contact with said knuckle when the hinge is in open position.

6. In combination with a pair of hinged leaves, a wire spring having an upper portion curved in a laterally extending plane, a 10 curved intermediate portion connected with

said upper portion and extending obliquely across and around the knuckle of the hinge, and a lower portion curved in a laterally extending plane, the top of said upper portion being pivoted to the outer portion of one hinge leaf and bottom of said lower portion being pivoted to the outer portion of the other hinge leaf. 15

JOHN M. SHIELDS.
